LOOM AND VIBRATION CONTROL
THEREFOR

Nelson A. Batchelder, West Barrington, R. I., assignor to Woods Manufacturing Company, Limited, Montreal, Quebec, Canada, a corporation of Canada

Application March 19, 1938, Serial No. 196,933

6 Claims. (Cl. 248—21)

My present invention relates to looms, and aims to improve their general operation, at higher speeds, or with less breakage, by directing and controlling the various forces which have heretofore had an outlet only by way of wracking and excessive vibration of the whole loom frame and the underlying flooring.

In the drawings illustrating one embodiment of the invention by way of example,

Fig. 1 is a side or end view of a loom having the means of the invention incorporated with it, and illustrating especially the lay and picking motions and their particular operative relation to said means;

Fig. 2 is a horizontal section as on the line 2—2 of Fig. 1, on a larger scale, showing the loom shock-absorbing and buffer mechanism or unit at the right front portion of the loom;

Fig. 3 is a side elevation of said loom parts of Fig. 2;

Fig. 4 shows the same as viewed from the left in Figs. 2 and 3, with portions in section;

Fig. 5 is a similar view but looking from the right; and

Fig. 6 is a longitudinal section as on the line 6—6 of Fig. 2, with portions in side elevation.

The speed at which looms may be economically operated has heretofore been limited to a large extent by the resulting shock and vibration affecting the various loom parts and the flooring on which the loom is located. Considerable relief in this respect may be had by the use of governor means such as disclosed and claimed in a copending application, whereby the unbalanced motions of a loom are smoothed out to a marked extent. For installations where the looms are rigidly supported, as on a ground floor or one adequately braced and reinforced, looms so equipped may be speeded up without introducing further problems of vibration effects. In other instances, however, particularly in older mills and at locations above the ground floor, maintained loom speeds much above 150 picks per minute are found impractical, as the attendant increased frame and floor vibration tends to offset the advantages gained from the higher speed of operation.

My present invention provides means for counteracting objectionable vibratory effects in loom operation, whether at ordinary or abnormally high speeds, serving in any case to decrease production costs by reducing the breakage of parts. Such means, as above indicated, may be employed in combination with my loom governor mechanism further to increase the field of usefulness of the latter, or alternatively to or independently

of such governor mechanism, as the particular circumstances and conditions for the given installation may determine. And while the present invention is especially applicable to the increasing of loom speeds in any instance where the attendant vibratory effects would make such increase unprofitable or dangerous, it is also useful in providing for a more efficient and economical operation of substantially any power loom.

The causes of the excessive shock and vibration inherent in the operation of a loom, and the manner in which they are to a large extent dissipated in accordance with my invention will readily be understood from a consideration of Fig. 1. Referring to the latter, the right loom side or frame is indicated at 1 and its front and rear supporting feet at 2 and 3. At the front of the loom is the usual breast beam 4 and at the rear are the bearings 5 for the warp beam, not shown.

As customary, the lay 6 is mounted to swing forwardly and back with the lay swords 7 on the rock shaft 8, seen at the lower left corner portion of Fig. 1, well toward the front of the loom. The lay is operated in the usual manner by the crank shaft 9 having cranks 10 connected to the lay through pitman arms 11.

The lay is shown in full lines in Fig. 1 in its forward or beating up position, and in dotted lines in its rear or back center position approximately as during the delivery of the shuttle across it. The vigorous swinging of the lay between these two positions is an unbalanced action involving considerable shock and violence, particularly in the beating up of the weft into the fell of the goods as the lay comes to its extreme forward position. The center about which this movement takes place, namely the axis of the rock shaft 8, is far offset from the center of gravity of a loom as a whole. Hence the swinging movements of the lay have not only a fore and aft component tending to displace the loom in the direction from front to rear but also have a substantial vertical component tending to rock or tilt the loom relative to the flooring or to move the latter vertically with the loom.

Other shock and vibration effects come from the violent picking action by which the shuttle is thrown back and forth across the lay. Referring still to Fig. 1, the right picker stick is seen at 12. It is mounted in the usual way so as to swing with the lay about the rock shaft 8 and is pivoted at its lower end so that it may be thrown or picked lengthwise the lay. This picking action is effected from the cam shaft 13 on which

are mounted the pick cams 14, one for each side of the loom. The steep pick point 15 of the respective pick cam engages at each revolution of the cam shaft with the pick ball 16 on the 5 rocking picker shaft 17 connected through the pick arm 18 and sweep stick 19 to the lower portion of the picker stick 12, by means of the lug strap 19a. It will be noted that the sharp pick point 15 strikes its pick ball with substantially a 10 hammer blow, by reason of which and the large leverage involved in the several parts the picker stick is thrown with sufficient force to project the shuttle across the lay. This action, taking place alternately at the two sides of the loom, tends to 15 skew or kick first one side of the loom and then the other side out of position. There is also a substantial upwardly thrusting component involved in the engagement of the pick point with the pick ball, tending to lift the loom bodily or to 20 raise the flooring with it.

In accordance with my invention these several forces and their various components are in effect resolved and caused to act in a single direction, fore and aft of the loom, by permitting the loom to have a bodily movement in said direction, in the course of which the various otherwise conflicting forces are so directed and controlled that they may be absorbed and dissipated, rather than going to the production of the objectionable vibratory and shock effects on the loom parts and the supporting flooring. The invention accordingly contemplates means whereby the entire loom may have a directed fore-and-aft movement, against a controlled resistance, in the performance of which movement the otherwise restrained forces which ordinarily produce the objectionable wracking and vibratory effects, are given a free outlet and are expended and absorbed in a non-harmful manner. 30

Such means as herein illustrated comprises shock-absorber and buffer mechanism incorporated with loom-supporting track devices structurally combined with and interposed between the loom frames and the flooring, said mechanism including a plurality of similar units symmetrically arranged at the two sides of the loom. The front and rear units for the right side of the loom, associated with the feet portions 2 and 3 of the frame, are seen in Fig. 1, the 35 other side of the loom being similarly equipped.

In Figs. 2 to 6 the unit for the right front foot portion 2 of the loom is shown in detail, as typical of the others. The frame foot has integrally or otherwise rigidly secured to it a slide or shoe 20, as by means of stud bolts 21 extending through the loom foot and into the shoe. The latter comprises a plate having flat running surfaces 22 along its under longitudinal side portions and a depending intermediate rib 23 of 0 dovetailed section. This rib is received in a correspondingly shaped way formed between parallel rails 24 on the upper face of an underlying fixed base or track plate 25. The inner opposed faces of the rails 24 are undercut or bevelled as 5 indicated at 26, 26 for cooperation with the dovetailed rib 23 on the movable shoe 20. Hence the described construction not only provides for straight-line guided movement of the shoe on the base plate but also prevents relative vertical 10 movement between these two main parts. The track plate or base 25 is adapted to be firmly secured to the flooring by bolts or the like 27, Fig. 1, passing through toes 28, one at each corner portion of the base plate in the illustrated example.

The track plate 25 and the shoe 20 desirably have formed at a central portion of their opposed faces oppositely disposed recesses 29 and 30, see particularly Fig. 4, together providing a chamber or reservoir for grease or other lubricant. Distributing channels 31, which may be drilled or formed as grooves in the bearing faces either of the track plate or of the shoe, or both, serve to conduct the lubricant to the various bearing portions, whereby all contacting faces of 10 these two main members are assured of adequate lubrication, facilitating the guided movement of the shoe relative to the track plate. Lubricant is supplied through a filling channel 32 communicating with the grease chamber 29, 30 15 and having a closure plug 33. This chamber or reservoir is adapted to contain sufficient lubricant for long periods of operation, assuring continuous smooth operation of the parts with but infrequent attention. 20

The movement of the loom and the series of shoes 20 relative to their respective track plates 25 is adjustably controlled and limited by buffering and shock-absorbing mechanism illustrated as of a compound character. On each 25 shoe 20 is a side lug or laterally projecting abutment piece 40. This piece is arranged to face a similar abutment piece or side lug 41 on the corresponding track plate 25.

Between this pair of abutment pieces 40, 41 30 of each unit is a heavy compression spring 42 of the coil type. One of said abutment pieces, herein the element 40 on the movable shoe, has a boss 43 receivable in and positioning the adjacent end of the spring 42. At its other end 35 the spring is seated and positioned by a corresponding boss 44 on a seating disk or member 45 which is adjustable relative to the adjacent abutment element 41, on the fixed track plate 25. Said fixed abutment piece 41 has threaded 40 centrally through it an adjusting screw 46 having a rounded inner end 47 received in a corresponding recess in the outer face of the spring seat 45. A locking nut 48 assists in holding the adjusting screw 46 and spring seat 45 in adjusted position, thereby accurately to regulate the normal compression of the spring 42. The parts are assembled and adjusted so that the spring 42 is under an initial compression adequate to keep the spring and associated parts in 50 seated position.

Additional means is provided in operative combination with the compression spring for cushioning and limiting the extent of approach of the movable abutments 40 on the loom toward the fixed abutments 41 on the base plates secured to the flooring. For this purpose I have herein provided in each unit a pair of substantially hemispherical oppositely disposed buffer elements 50, 51 formed of rubber or other 55 durable resilient material. These members 50, 51 have their flat diametral faces oppositely adjacent each other in opposed recesses or cups in a sleeve-like holder element 52 loosely received and positioned within the coil spring 42. 60

Referring again to Fig. 1 it will be noted that the fixed member of the pair of opposed abutment elements 40, 41, in this instance the element 41 which carries the adjusting screw 46, is disposed in the forward position in the shock-absorbing or buffer assembly units located at the front of the loom, as in conjunction with the right front loom foot 2 of Fig. 1, so that it opposes and limits the forward motion of the loom. The same is true for the unit in front position 75

at the other side of the loom, the shoes and base plates being constructed as rights and lefts, that is, with the abutment pieces in one instance projecting to the right and in the other case projecting to the left. Similarly, the absorber units which are disposed at the rear of the loom, such as in connection with the rear foot 3 of Fig. 1, have the fixed abutment element 41 in rear position, to oppose and limit the loom movement 10 in the rearward direction. It will be obvious that a "right hand" unit, such as appropriate for example for the position at the front right foot 2 of the loom is also suitable for the rear left foot of the loom, by reversing the unit end 15 to end. A series of four such units in opposed pairs at the two sides of the loom have been found adequate for most installations but one or more additional units or pairs of units may be provided if desired, the base plates which are 20 secured to the floor being common to a plurality of shoe members slidably thereon or being separately formed for each shoe, as may be more convenient.

The various stresses and strains accompanying 25 the operation of a power loom and transmitting their effects to the loom sides and through them to the flooring have been referred to in the opening portion of the specification and will be readily apparent to those familiar with the weaving art. 30 The essential motions of the loom parts while regularly timed in their action are unbalanced and irregular in their resultant effects on the loom frame. As the lay surges forward it tends to throw the entire loom forward and to lift 35 the back feet of the loom. In its return it has the reverse tendency not only to shift the loom rearward but also to throw the rear feet down. Before the lay reaches the end of its back swing the picking mechanism works at one side of the 40 loom, with a further tendency to throw the loom back as well as producing a skewing or laterally disturbing effect. This picking action and its effect on the loom frame may be compared with the action of rowing a boat wherein the rower pulls first a full stroke on one oar and then on 45 the other one, with the effect of throwing the boat out of line on each stroke, first to the right and then to the left. And the total effect of the powered actions in a loom may by similar analogy be likened to two oarsmen in tandem, one 50 pulling his two oars alternately, representing the picking motion as just referred to, and the other pulling a regular stroke with his two oars simultaneously, representing the action of the lay beam. Where, as in a loom, such unbalanced forces are attempted to be harnessed and restrained within a frame fixed to the supporting flooring, excessive vibratory and wracking effects are inevitable, especially at higher operating speeds.

The mechanism such as herein illustrated and described, by permitting the loom frame to move bodily, resolves and reduces the total effect of these unbalanced movements to a single straight-line fore and aft movement which is accurately aligned and guided both in the horizontal and in the vertical planes, through the medium of the track and slide formations described. The energy otherwise going to produce objectionable 60 vibration of the whole loom is thus given a controlled outlet so that it is harmlessly expended, the greater portion of it being taken up in the compression of the absorber springs while any remaining or final portion is absorbed and dissipated by the buffering action of the distort-

able hemispherical elements. The shape of these latter is such that their resistance to distortion increases immensely with the increasing pressure. The several parts, further, are so proportioned and constructed that the distortable buffering elements complete their absorbing and movement-limiting action before the springs close completely upon themselves, thus avoiding any final shock or jar such as might result from contact of metal on metal.

It will be understood that the total bodily movement of the loom is extremely limited, being generally in the order of but a fraction of an inch, approximately $\frac{1}{8}$ to $\frac{1}{4}$ of an inch in the average case. The described adjustments 15 enable the action of the springs to be nicely regulated and balanced properly to distribute the absorbing and buffering action among the several units to suit the individual requirements and 20 conditions for any given loom.

It will thus be seen that in accordance with my invention I have provided in a loom structure novel means designed and operating with peculiar reference to and operative combination with the various loom motions, and with special 25 relation to the stresses and strains which are typical of a loom. As a result the speed of a given loom can be substantially increased without additional or objectionable vibration, in cases where increased speed is an important objective. In other cases the normal or existing speeds may be maintained but with a substantial reduction in the breakage of parts and corresponding saving in overhead.

My invention is not limited to the particular 30 embodiment thereof illustrated and described herein, and I set forth its scope in my following claims.

I claim:

1. In a machine such as a power loom having a supporting frame subject in the operation of the machine to unbalanced forces having horizontal fore-and-aft and lateral components and also vertical components, the combination with the machine frame of stationary track elements 40 symmetrically disposed at the base of said frame and extending in the direction from front to rear of the machine, slide plates on the base of the machine frame adjacent each track element and having guide formations cooperating with said elements, including means preventing relative vertical movement between the track elements and slide plates, whereby the machine frame may move bodily on said track elements solely in a guided straight-line forward and back direction, 45 and shock-absorbing and buffering mechanism operatively interposed between the corresponding track elements and slide plates thereby to control and limit said movement and to absorb and dissipate the energy producing the same and 50 which in the absence of said permitted movement causes objectionable wracking and vibration of the machine as a whole.

2. In a machine such as a power loom having supporting side frames subject in the operation 65 of the machine to unbalanced forces having horizontal fore-and-aft and lateral components and also vertical components, each side frame having an underlying stationary base plate formed with a track parallel to its side frame, shoes fixed on 70 the side frames and slidably received by the base plates for guided movement along the tracks thereof, abutment formations projecting laterally of the side frames in opposed paired relation on the shoes and base plates respectively, and 75

compressible shock-absorbing buffer devices operatively interposing the abutments of each pair.

3. In a machine such as a power loom having supporting side frames subject in the operation of the machine to unbalanced forces having horizontal fore-and-aft and lateral components and also vertical components, one or more supporting track members for each side frame and cooperating shoes fixed on the side frames so as to provide for guided movement of the frame as a whole in the forward and back direction, said track members comprising base portions adapted to be secured to the flooring and having horizontal and lateral guide surfaces cooperating with like-disposed surfaces on the shoes, and means to limit and control the movement of the frames and shoes relative to the track members, each shoe and its receiving track member having a lubricant reservoir and passages communicating between the reservoir and said cooperating guide surfaces continuously to supply the latter with lubricant.

4. Mounting means for a power loom to reduce the shock and vibration effects thereof, said means comprising shoes adapted to be fixed at the base of a loom frame, symmetrically at both sides, stationary track elements disposable in parallelism with the loom sides and slidably mounting said shoes, opposed abutments for each shoe and its corresponding track element, and coil springs operatively positioned between the corresponding abutments of the shoes and track elements so as to be compressed by approach of the shoe abutment toward that of its track element during bodily movement of the loom to be supported.

5. Mounting means for a power loom to reduce the shock and vibration effects thereof, said means comprising shoes adapted to be fixed at the base of a loom frame, symmetrically at both sides, stationary track elements disposable in parallelism with the loom sides and slidably mounting said shoes, a pair of opposed abutments for each shoe and its corresponding track element, a coil spring operatively positioned between the abutments of each pair so as to be compressed by approach of the shoe abutment toward that of its track element, and distortable buffer means within said springs and cooperable with said abutments to limit the spring compression and further resist the approach of the shoe and track abutments during bodily movement of the loom to be supported.

6. Mounting means for a power loom to reduce the shock and vibration effects thereof, said means comprising shoes adapted to be fixed at the base of a loom frame, symmetrically at both sides, stationary track elements disposable in parallelism with the loom sides and slidably mounting said shoes, interlocking guide means confining the movement of the shoes relative to the track elements to a rectilinear horizontal movement only, pairs of opposed abutments, one on each shoe and the other on the corresponding track element, and resilient shock-absorbing buffer means operatively interposed between said abutments of each pair to control the movement of the shoe abutment toward that of its track element during bodily movement of the loom to be supported.

NELSON A. BATCHELDER. 35
